ARTHUR H. ADAMS, OF SPARKILL, NEW YORK, AND LIPA POLINKOWSKY, OF LONDON, ENGLAND, ASSIGNEES TO WESTERN ELECTRIC COMPANY, INCORPORATED, OF NEW YORK, N. Y., A CORPORATION OF NEW YORK.

AUTOMATIC CIRCUIT-CHANGING SWITCH.

1,254,642.

Specification of Letters Patent. Patented Jan. 29, 1918.

Application filed August 4, 1916. Serial No. 113,106.

To all whom it may concern:

Be it known that we, ARTHUR H. ADAMS, a citizen of the United States, residing at Sparkill, Rockland county, New York, and 5 LIPA POLINKOWSKY, a subject of the Czar of Russia, residing at 70 Westbourne Terrace, London, W., England, have invented new and useful Improvements in Automatic Circuit-Changing Switches, of which the following is a specification.

The invention relates to automatic circuit changing switches of the type in which an operating member is adapted to be moved through a plurality of positions in each of 15 which certain circuit changes are accomplished. The embodiment of the invention disclosed herein is designed more particularly for use in automatic telephone systems and is adapted to be used as a register or 20 register controlling device.

Switches of this general character are well known and they are adapted to be used in automatic telephone systems where it is desired to register or store controlling impulses and to subsequently control automatic apparatus, in accordance with the impulses so registered and stored. Devices of 25 this general character are shown as applied to telephone systems in Patent No. 1,157,881 30 of October 26, 1915, to McBerty.

The object of the present invention is to provide a switch of this character in which both the registering and controlling movements may be accomplished reliably and in 35 which the movements of the switch from position to position may take place in a minimum of time, that is in which the operating parts of the switch are quick acting. These objects are obtained in the present 40 device by the employment of a spring driven cam barrel which carries the cams for operating the various contact springs and controlling the motion of such cam barrel by means of an electromagnetic escapement 45 mechanism. By virtue of this construction the movement under the control of the escapement mechanism from position to position is very rapid. Means are also provided for winding up the spring which drives the 50 cam barrel at the end of a cycle of operation of such cam barrel. Further than this, a plurality of cam barrels which are mutually independent of one another may be

mounted on a common shaft and the driving springs thereof wound up by a common 55 driving mechanism. Thus a complete registering and controlling equipment comprising several registers may be assembled in a very compact manner.

The invention will be best understood by 60 reference to the accompanying drawings, in which—

Figure 1 is a plan view of the switch with a portion of the frame broken away to more clearly disclose the escapement mechanism; 65

Fig. 2 is a side elevation with the cam barrel shown in section;

Fig. 3 is a side elevation of the upper portion of the switch at right angles to the view of Fig. 2 in order to show more clearly 70 the arrangement of the contact springs;

Fig. 4 is a diagrammatic view of a portion of the winding mechanism; and

Fig. 5 is a type of circuit arrangement with which the switch disclosed is adapted 75 to be employed.

Referring now to the drawings, 1 designates the frame a forwardly projecting part 2 of which forms a bearing for the shaft 3. Upon the shaft 3 a plurality of cam barrels 80 4 are mounted being held in position between the collars 5 and 5^a which are fixedly secured to the shaft. Secured to the top of each cam barrel 4 is a toothed escapement wheel 6 with the teeth of which an escapement lever 7 is adapted to coöperate. The lever 7 is secured to the armature 8 of an electromagnet 9. The armature 8, together with the lever 7 carried thereby is pivoted to the frame on a pair of screws 10 only one 90 of which is shown in the drawing. A spring 11 attached to one end of the lever 7 and at the other end to the projection 12 on the frame, serves to maintain the lever with its outer end in its raised position. The cam 95 barrel 4 carries a plurality of cams 13 which coöperate with sets of contact springs 14, 15 and 16. There are as many cams provided on the cam barrel and sets of contact springs mounted on the frame which coöperate therewith as are necessary to bring about the circuit changes required by the particular system with which the switch is adapted to operate, the number varying with different circuits and systems. As 100 105 shown more particularly in Fig. 2, the con-

2

tact springs 14, 15 and 16 may be of different widths in order to more easily coöperate with the cams and to permit the cams being relatively narrow. The arrangement 5 of the cams is such that the spring 15 may be brought into contact with either the springs 14 or 16. The escapement wheel 6 is provided with as many teeth as there are positions in which the switch may stop, with 10 the exception of one position which will be referred to as the sub-normal position, in which the cam barrel is held in position independent of the escapement mechanism. The number of positions in which any given 15 switch may stop is determined by the requirements of the circuit arrangement with which it is to be used and may be varied to suit any requirement by varying the number of teeth on the escapement wheel.

20 In the arrangement disclosed there are 10 positions and a sub-normal position for the switch, hence there are ten teeth and a space on the wheel which is not provided with a tooth intermediate the first and last positions, 25 which position for convenience will be referred to as a sub-normal position. Attached at one end of a collar 5^a fixedly secured to the shaft is a spiral spring 17 which surrounds a shaft 3 and which is attached at its other end to the cam barrel 4. This spring when suitably wound up by a 30 mechanism which will be hereinafter described serves to drive the cam barrel under the control of the escapement wheel 35 through the various positions, as determined by the teeth on the escapement wheel.

As indicated in Figs. 2 and 3 there may be and preferably are a plurality of the cam barrels 4, escapement mechanisms 6, 7, 8 and 40 escapement magnets 9, there being as many barrels and escapement mechanisms provided as demanded by the requirements of the system to which the switch is to be applied. All of these barrels and escapement mechanisms are identically the same in construction and need not further be described.

In order to wind up the spring 17 a form 45 of magnetic clutch is provided comprising the disks 18, 19 and the clutch magnet 20. The disk 19 is driven from a constantly rotating shaft 21 and when the magnet 20 is energized the disk 19 is drawn into contact with the disk 18 and drives the shaft 3 attached to the disk 18 for the purpose of 50 winding up the spring 17. Also mounted on the disk 18 is a disk 22 which coöperates with a roller 23 carried by a spring arm 24 which arm carries an insulated piece 25 adapted to operate the contact springs 26 and 60 27.

As shown in Fig. 1 the collar 5 of each register is provided with a projection 28, which is adapted to engage with the pin 29 65 to hold the cam barrel 4 in the subnormal

position, the parts being shown in Fig. 1 in such sub-normal position. In this position suitable circuits are closed for the clutch magnet 20 and the shaft 3 is driven through one revolution in the direction of 70 the arrow, Fig. 1, to wind up the springs 17 of all the cam barrels. As soon as the shaft 3 leaves the position of rest the escapement wheel 6 moves from its sub-normal position until the escapement lever engages 75 and holds the first tooth 30 in which position the cam barrel is held until permitted to move by the energization of the escapement magnet. This position is the home or zero position of the cam barrel. Also as 80 soon as the shaft 3 begins to move the wheel 23 rides out of the depression on the disk 22 and operates the contact springs 26 and 27 which maintains a circuit for the clutch magnet 20 until the wheel 23 again enters 85 the depression on the disk 20 and opens such circuit and stops the shaft, thus the shaft 3 makes a single revolution in its winding operation. When the shaft 3 has completed this winding movement as above described 90 and stops, the projection 28 will occupy the position shown in Fig. 1 but in this case owing to the fact that the tooth 30 has moved over into contact with the end of the escapement lever 7, the pin 29 will be 95 on the opposite side of the projection 28 from that shown in Fig. 1. It will be observed that the escapement lever 7 is provided with two projections or teeth 31 and 32, the projection 31 being adapted to engage 100 a tooth on the escapement wheel 6 when the magnet 9 is energized and the projection 32 being adapted to engage the tooth when the magnet is deenergized. As a result of this arrangement and as is common in 105 escapement mechanisms of this class, the escapement wheel 6 will move the complete distance from one tooth to another in two steps moving a portion of such distance upon the energization of the magnet and the 110 remaining portion upon the deenergization thereof. The spacing of the teeth upon the escapement wheel relative to the spacing of the projections of the escapement lever may be chosen so that these two movements are 115 equal, that is to say, when the movement from tooth to tooth of the escapement wheels is in two equal steps or the arrangement may be such that one of these steps is considerably longer than the other. However, 120 for convenience in describing the operation of the device these two steps of movement will be referred to as the first and second half-steps, it being understood that these two half-steps together cause a movement of 125 the escapement wheel and the cam barrel controlled thereby through one position, that is to say, from one tooth to the next tooth.

It follows from the above, therefore, that 130

with the escapement wheel and the cam barrel in the home position that ten energizations and deenergizations of the escapement magnet 9 will be necessary to move the escapement wheel and cam barrel from the home position to the sub-normal position.

Referring now to Fig. 5 in which is shown a circuit arrangement with which the switch forming the subject of the invention is adapted to operate, as a register and controlling equipment. In the arrangement shown the registering and controlling equipment comprises four registers indicated generally by the escapement magnets 9^a, 9^b, 9^c and 9^d. Each of these registers comprises in addition to the escapement magnet a cam barrel and a plurality of contact springs operated thereby, however, only two sets of contact springs are shown and the cam barrels are not shown. The springs individual to each register are inclosed in the dotted line rectangle in which the escapement magnet is also inclosed. All of the cam barrels of the registers forming the equipment are mounted on a common shaft which is operated by a common winding mechanism of which only the clutch magnet 20 is shown. Also as shown the registers are constructed to have eleven positions indicated from 0 to 10 of which position 0 is the normal or home position and 10 is the sub-normal position. Incoming and outgoing sequence switches 100 and 200 are common to the equipment and the interrupter 305 is common to a number of equipments.

The line "a" leads to an impulse sender (not shown) which may be the usual sending device at the subscriber's substation or an operator's sender depending upon whether the register and controlling equipment is used in connection with an automatic or a semi-automatic system.

As soon as the registering and controlling equipment is taken for use the line "a" is connected through suitable switches (not shown) and a circuit is closed for the stepping relay 300. The energization of the relay 300 drives sequence switch 100 into position 3 over contact 101 top. In position 3 of the sequence switch 100, contact 102 top is closed and as the relay 300 is still energized a circuit is closed for the escapement magnet 9^a of the first register and the cam barrel thereof moves from position 0 one half-step. The impulse sender is now operated and interrupts the circuit of the relay a number of times equal to the complement of the desired digit. For each interruption or impulse the stepping relay 300 is deenergized and energized and the escapement magnet 9^a is correspondingly deenergized and energized permitting the cam barrel to move through as many positions as there are impulses sent over the line "a".

This movement of the register under the

control of impulses from a sending device is known as the setting or registering movement. As is usual the setting impulses for each digit are followed by a long impulse, in the case assumed a long interruption. As 70 the result of this long interruption the line relay 300 is deenergized for a period long enough to permit the slow acting relay 301 to operate over a circuit including contact 103 bottom. The operation of relay 301 75 drives the sequence switch 100 into position 6, in which position contact 102 bottom is closed and the second register 9^b is placed in operative relation with the stepping relay 300. It may be stated here that in the 80 system disclosed owing to the interoperation of the sequence switches 100 and 200, one register may be and usually is performing its controlling operation while a subsequent register is being set, but for convenience 85 and for the sake of clearness the setting of all the registers will first be described and then the controlling operation will be described.

In the normal operation, unless the call 90 has been abandoned, the circuit to the impulse sender will have been closed before the sequence switch 100 reaches position 6 so that relay 300 will be energized and when the sequence switch 100 reaches position 6, the 95 escapement magnet 9^b will be energized and the register will move one half-step. This register will now be set in response to the second series of impulses from the impulse sender in the same manner as the first register. The long impulse at the end of this series of setting impulses will as before cause the operation of the slow acting relay 301, which will drive the sequence switch 100 into position 100. When the sequence 105 switch 100 reaches position 9, relay 300 will be again energized and a circuit for the escapement magnet 9^c of the third register will be established over sequence switch spring 107 and this register will be moved a half-step. 110 This register will now be set in response to the third series of setting impulses in the manner above described. The long impulse which follows this series of setting impulses will as before described cause the operation 115 of the slow acting relay, which will drive the sequence switch 100 into position 12.

In position 12 of the sequence switch 100, the relay 300 being energized, a circuit will be established for the escapement magnet 120 9^d of the fourth register, causing such register to move through its first half-step. In response to the fourth series of setting impulses the fourth register will be set, and the long impulse which follows this series 125 will cause the operation of the slow acting relay 301, which will drive the sequence switch 100 into position 15 in which position it will wait for the completion of the controlling operation of the registers. 130

The leads indicated at *b* and *c* at the upper right hand portion of the figure form a part of the controlling or fundamental circuit extending to selector switches which are to be controlled from the registering and controlling equipment. These switches may be of any well known type and for convenience in description will be assumed to be of the type disclosed in the patent referred to above, in which an interrupter device operated by the switch in its movement operates to shunt the stepping relay indicated at 302, once for each step or stage of movement of such switch.

15 When the sequence switch 100 reaches position 4, immediately after the first register has been set, a circuit is closed at spring 104 over spring 201 to drive the sequence switch 200 into position 3. In this position the fundamental circuit is closed at spring 203 and the stepping relay 302 becomes energized. At the same time the selector switch is started in movement. It should be observed that in positions 3, 7, 9 and 11 sequence switch springs 202 and 208 connect the various registers successively in operative relation to the stepping relay 302. Although the fundamental circuit is also established in these positions at spring 203, it may happen that the fundamental circuit is not closed, and hence the relay 302 may not be energized soon enough to prevent the register associated therewith from moving through one half-step under the control of the back contact of relay 302. In order to avoid this possible false operation, the relay 304 is provided, which is energized in positions 2, 6, 8 and 10 of sequence switch 200 over spring 204 and is locked up over a circuit from battery, 304, front contact thereof, 211 and back contact of 302 to ground. Therefore, in all cases the relay 304 maintains open the circuit from 302 to the registers until after the fundamental circuit is closed and relay 302 is energized.

Assuming now the sequence switch 200 in position 3 and the relay 302 energized, and relay 304 deenergized, as the selector switch under control moves the relay 302 will be shunted and consequently deenergized for each step or stage of movement of the selector switch. For each deenergization and energization of the relay 302 the escapement magnet 9^a will be energized and deenergized and will step the register from position to position until position 10 is reached when a circuit will be established from back contact of relay 302, register springs 401, 400, spring 205, to cut off relay 303 and sequence switch 200 in parallel. The operation of relay 303 will open the fundamental circuit and stop the movement of the selector switch and the sequence switch 200 will move into position 4 and will wait in such position until the sequence

switch 100 moves into position 7 after the second register has been set. When the sequence switch 100 reaches position 7, assuming as is the case in an operative system that a second selector has been also associated with the fundamental circuit, a circuit will be closed over contact springs 105 and 206 to drive the sequence switch 200 into position 7, in which position the second register is associated with the stepping relay 302. The controlling movement of this register takes place in the same manner as the corresponding movement of the first register and when it reaches position 10 a circuit is closed from the back contact of the relay 302, through springs 202, 501, 500, 401, 400, 205 to cut off relay 303 and sequence switch 200. The operation of relay 303 opens the fundamental circuit and permits the extension of such circuit to another selector switch. The sequence switch 200 moves into position 8 and there waits until the third register has been set. When the sequence switch 100 reaches position 10 a circuit is closed at contact 106 over contact 206 to drive sequence switch 200 into position 9. In position 9 the third register and its escapement magnet 9^c is placed in operative relation to the stepping relay 302 by means of contact 208. This register now operates in its controlling movement and in conjunction with the stepping relay controls the selector switch. When this register reaches position 10 a circuit is closed from the back contact of the relay 302, through contacts 208, 601, 600, 501, 500, 401, 400, 205 to relay 303 and sequence switch 200. The operation of 303 opens the fundamental circuit and stops selection in the selector switch and at the same time the sequence switch 200 moves into position 10 and waits until the last register has been set, when the sequence switch upon reaching position 13 closes a circuit over contacts 108 and 210 to drive the sequence switch 200 into position 11, in which position the last register will be associated with the stepping relay 302, and the fundamental circuit will be re-established. The last register will now control selection and when it reaches position 10 a circuit will be closed from the back contact of relay 302, through contacts 208, 701, 700, 601, 600, 501, 500, 401, 400, 205, to the cutoff relay 303 and the sequence switch 200. The operation of relay 303 opens the fundamental circuit and stops selection in the selector switch and the sequence switch 200 will move through positions 12 to 18 and back to position 1. The sequence switch will not stop in position 13 as in position 13 a circuit is closed for the sequence switch from interrupter 305, over springs 205, 400, 500, 600, 700, 208 and 209. As the sequence switch is passing through positions 14 to 16 as all of the registers are

now in position 10, the sub-normal position, a circuit is closed for the clutch magnet 20 of the winding mechanism from ground at contact 209, contacts 208, 701, 700, 601, 600, 5 501, 500, 401, 400, 205 to 20 and battery. This starts the winding mechanism to operate. As explained in connection with the construction of the registers as soon as the winding mechanism is started the various 10 cam barrels will move from the sub-normal position to the home or normal position, the winding mechanism will however continue to operate under the control of the contact 800 until the winding shaft has completed a complete revolution, when the contact 800 will be opened. When the sequence switch 200 reaches normal position the contact 207 will be closed and will drive the sequence switch 100 into position 1 over contact 101. As soon as the sequence switches 15 100 and 200 reach position 1 the registering and controlling equipment may be again taken for use and as all of the registers are in the normal position the setting operation 20 of the registers may begin before the winding mechanism has completed its operation as this will not interfere in any way with the operation of such winding mechanism.

Having thus described the normal operation 25 of the system, the operation of the system will now be described in the event that the call is abandoned at any time before the controlling operation of the registers is completed. As the operation will be the same 30 in principle whether the call is abandoned immediately after the registering controlling equipment is taken for use or whether the call is abandoned just before the controlling operation of the last register is completed, the first case will be assumed. It 35 will be recollect that as soon as the circuit from the impulse sender was extended to the registering and controlling equipment the relay 300 was energized and the sequence switch 100 moved to position 3. When this 40 position was reached the first register was moved through the first half step. If the call is abandoned at this point the circuit of the relay 300 will be opened and will remain 45 open; therefore the slow acting relay will be energized and will remain energized until the sequence switch 100 leaves position 50 12. As the result of the energization of the relay 201, the sequence switch 100 will move 55 from position 3 direct to position 15, and as the relay 300 is still deenergized a circuit will be closed at contact 103 in position 15 to drive the sequence switch to position 18. In 60 passing positions 4 to 6 a circuit is closed at contact 104 to drive the sequence switch 200 into position 3 and when the sequence switch 100 reaches position 18 a circuit is closed including contacts 104 and 201 to drive the sequence switch 200 into position 13. In this 65 position the interrupter will be connected to

the escapement magnet 9^a over contacts 209, 208 and 701 and the last register will be stepped around under the control of the interrupter until it reaches the subnormal or position 10. In position 10 of this register 70 the contact 701 is opened and the contact 700 is closed so that the circuit from the interrupter is extended to the escapement magnet 9^c of the third register, causing this register to be stepped around to its tenth position. 75

When this register reaches position 10 the circuit from the interrupter will be extended over contacts 600 and 501 to the escapement magnet 9^b of the second register and this 80 register will be stepped around into its tenth position, in which position the circuit contacts of the interrupter will be extended over contacts 500 and 401 to the escapement magnet 9^a of the first register. As this register 85 was moved through the first half step upon the first energization of the relay 300, it is obvious that upon the deenergization of this relay when the call was abandoned the register will have moved through the other half 90 step into position 1. Therefore, when the circuit from the interrupter is extended to the escapement magnet 9^a this register will move into position 10 and in such position the next impulse from the interrupter will 95 be directed over contacts 400 and 205 to the sequence switch 200 to drive it out of position 13 into position 1. In passing positions 100 14, 15 and 16 a circuit will be closed for the clutch magnet 20 over contacts 209, 208 and 205, thus starting the winding mechanism into operation. When the sequence switch 200 reaches position 1 a circuit will be closed at contact 207 to drive the sequence switch 100 into its normal position and the 105 registering and controlling equipment may be again taken for use. It will be apparent from the above that if any of the registers have been moved out of their normal position and the call is abandoned, all of the 110 registers will be stepped around to their subnormal positions and thus all of the driving springs unwound so that the operation of the winding mechanism will wind up all of the springs an equal amount. 115

What is claimed is:

1. In an automatic circuit changing switch, a rotatable shaft, a plurality of operating members independently and loosely mounted thereon, a plurality of springs one for each 120 of said operating members, one end of each spring being connected to said shaft and the other end to its respective operating member, individual means for independently moving said operating members, and a common means for subsequently rotating said shaft to wind up said springs.

2. In an automatic circuit changing device, a rotatable shaft, a plurality of independently operable members mounted on 130

6
said shaft, individual spring means for driving said members, individual escapement mechanism for said members for controlling the movement thereof, and a common means for rewinding said springs.

- 5 3. In an automatic circuit changing switch comprising a frame, a rotatable shaft held by said frame, a plurality of sets of switch springs mounted on said frame, a plurality of 10 sets of contact operating members independently and loosely mounted on said shaft adapted to operate said switch springs, spring means for driving said contact operating members, individual escapement means mounted on said frame for controlling the movement of said contact operating members, and a common means for rewinding said springs after said escapement means have been operated.
- 15 4. In an automatic circuit changing switch, a rotatable shaft, a plurality of independently and loosely operable members mounted on said shaft, each adapted when started to complete a cycle of movement and so interconnected that they are successively operated, individual spring means for driving said members, individual escapement mechanism for said members for controlling the movement thereof, and a common mechanism for rewinding said springs after the

20 last of said operating members has completed its cycle of movement.

5 5. An automatic circuit changing switch comprising a rotatable shaft, a plurality of contact operating members independently 35 rotatably mounted on such shaft, springs connected to such shaft and operating members and means for rotating such shaft to wind up said springs.

6 6. An automatic circuit changing switch 40 comprising a plurality of independently operable contact operating members, a plurality of springs for operating such members one for each of said contact operating members and a common means for rewinding such springs when the operating members have completed a cycle of operations.

7. A registering and controlling equipment for automatic telephone exchange systems, comprising a plurality of registers 45 each adapted when started to complete a cycle of movement and operative one after the other, a plurality of springs for driving such registers one for each register and mechanism common to the equipment for rewinding said springs, said mechanism being operated after the cycle of movement of the last operated register has been completed.
